UNITED STATES PATENT OFFICE.

CHARLES M. GOUGH, OF EAST ST. LOUIS, ILLINOIS, ASSIGNOR OF ONE-HALF TO JOHN KITTINGER, OF EAST ST. LOUIS, ILLINOIS.

PRESSING-PAD.

1,390,124.

Specification of Letters Patent.

Patented Sept. 6, 1921.

Application filed June 15, 1920. Serial No. 389,127.

To all whom it may concern:

Be it known that I, CHARLES M. GOUGH, a citizen of the United States, residing at East St. Louis, in the county of St. Clair and State of Illinois, have invented certain new and useful Improvements in a Pressing-Pad, of which the following is a specification.

This invention relates to pressing pads 10 for laundries, tailor shops, households and the like.

The object of the invention is to provide a pad of this character so constructed as to be substantially permanently resilient and which permits the free passage of steam 15 therethrough.

Another object is to provide a pad of this character equipped with simple and efficient means for securing it in operative position 20 on a steam board or buck.

Another object is to provide improved reinforcing means for such a pad.

With these and other objects in view, the 25 invention consists in certain novel features of construction as hereinafter shown and described and then specifically pointed out in the claim, and in the drawings illustrative of the preferred embodiment of the invention.

30 In the accompanying drawings:

Figure 1 represents a plan view of a steam chest for a pressing machine.

Fig. 2 is a top plan view of the pad constituting this invention.

35 Fig. 3 is a bottom plan view thereof.

Fig. 4 is a side elevation with parts broken out of the pad shown applied, and,

40 Fig. 5 is an enlarged detail sectional view of the pad shown applied to a steam chest parts being in elevation.

In the embodiment illustrated the pad constituting this invention is designed to be used in connection with a steam chest 1 of usual construction having the ordinary perforations 2 therein to permit the passage of steam from the chest through the pad which is secured to the top of the chest as is shown clearly in Figs. 4 and 5.

45 The pad 5 which constitutes this invention is composed of upper and lower layers of copper mesh wire 6 and 7 with coiled brass springs 8 interposed between the lay-

ers and secured thereto by soldering or otherwise.

Secured to the bottom of the pad and extending longitudinally thereof are two laterally spaced reinforcing rods 9 as is shown clearly in Fig. 3. Attaching means for the pad are shown in the form of a plurality of copper straps 10 which extend transversely across the bottom layer 6 of the pad under the rods 9 and have their ends projected laterally beyond the side edges of the pad being adapted to be bent down under the steam chest 1 as is shown clearly in Figs. 4 and 5. Similar straps 11 extend longitudinally from the ends of the pad and are here shown connected at their inner ends to the cross straps 10.

A covering 12 of any suitable fabric is arranged over the top, side and end walls of the pad and as shown has a layer of fibrous material 13 interposed between it and the top screen wire fabric 7 (see Fig. 5).

From the above description it will be obvious that a pad constructed as shown and described will be permanently resilient or substantially so and will yet permit the free passage of steam from the chest 1 in connection with which it is used up through the pad to the pressing surface thereof and which is desirable for pressing men's suits and the like. The covering extending around the sides and ends of the pad prevents the escape of steam to the surrounding atmosphere and directs it onto the pressing surface of the pad.

The preferred embodiment of the invention is disclosed in the drawings and set forth in the specification, but it will be understood that any modifications within the scope of the claim may be made in the construction without departing from the principle of the invention or sacrificing any of its advantages.

95 What I claim is:

A pressing pad composed of upper and lower layers of copper mesh wire with coiled brass springs between them and fixed thereto, laterally spaced reinforcing rods secured to and extending longitudinally of the bottom of the pad, a plurality of pliable metal attaching straps arranged transversely of said bottom under said rods with

their ends projecting beyond the side edges of the pad and adapted to be bent around a steam chest, similar straps arranged longitudinally of the ends of the pad and secured

of fibrous material interposed between it and the upper mesh wire, the bottom affording a substantially unobstructed passage 10 for the steam to the interior of the pad.

In testimony whereof, I affix my signature hereto.

CHARLES M. GOUGH.
